(57) **CLAIM**

The ornamental design for fastener, as shown and described.

DESCRIPTION

The fastener is used to secure a cable or a conduit to an angle iron. The fastener includes curved surfaces "E" for engaging the cable or conduit, and a pair of Flanges "F" joined together by a web "W" for receiving a portion of a band extending around the angle iron so that the fastener is pressed against the cable or conduit by the band to hold the cable or conduit firmly on the angle iron.

FIG. 1 is a perspective view of a fastener showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a rear elevational view thereof; and,

FIG. 7 is a left side elevational view thereof.
